AUTOMOBILE DOOR AND WINDOW LOCK

Henry M. Fredholm, Midlothian, Ill.

Application April 21, 1945, Serial No. 589,497

25 Claims. (Cl. 70—147)

1

This invention relates to automobile door locks. More particularly the invention is concerned with improvements in an automobile door latching mechanism and means for operating the same, being generally similar to that disclosed in my Patent No. 2,354,169, issued July 18, 1944, and embodies structural changes and improvements therein as well as added means in combination therewith whereby greater ease in the operation of the parts is accomplished.

The lock structure according to the said patent generally embodies a spring projected latching bolt, an outside door handle operatively engaged with a roll-back for retracting the bolt upon downward movement of the handle, a locking plate movable to positions for latching and unlatching the roll-back against bolt retracting movement and for bolt retracting movement respectively, an inside door handle having connecting means with the locking plate for moving same to its operative positions, said means including a lost motion connection with the latching bolt for retracting the same upon downward movement thereof, and means also cooperating with the inner handle to operate upon upward movement thereof to lock the handle against movement when the locking plate is moved to roll-back latching position.

The structure also includes key operable means for locking and unlocking the inner handle and shifting the locking plate to roll-back unlatching position as well as for shifting the locking plate to roll-back latching position and the inner handle to locked position.

In the structure of the patent, which is generally common with the present construction, the inner handle is movable against measurable friction occasioned by a swinging bolt embodied in the handle locking means, the same being spring-pressed against a guiding flange. Since the locking plate and inner handle move in unison by means of link connections therebetween, substantial effort is thus required to move the locking plate the required distance, with the result that substantial strain on the key is required to move the locking plate and inner handle to their respective positions in which the roll-back is latched or unlatched from the outer side of the door.

A primary object of the present invention is therefore an improved construction whereby the locking plate is movable a relatively short distance between roll-back latching and unlatching positions, thereby providing for movement of same with little effort, and thereby overcoming

2

the objections to the patented structure, wherein the inner handle is required to move a substantial distance by operation of the key.

A further object of the invention is the provision of key operable means for moving the locking plate to locking or unlocking positions together with means operative to automatically return the key to normal inserting and retracting positions of the key.

10. A still further object of the invention is the provision of visible signal means for indicating the latched or unlatched positions of the locking plate.

15. A still further object of the invention is the provision of improved locking means for the inside door handle.

20. A still further object of the invention is the provision of a locking plate which in roll-back latching positions locks the latch bolt against retraction, together with a novel keeper means permitting closing of the door when the latch bolt is so locked or unlocked.

25. With the above objects in view, together with others that will become apparent in the course of the following disclosure, reference will now be had to the accompanying drawings, forming a part of the invention, and wherein—

Fig. 1 is a side elevational view of the lock mechanism in a preferred embodiment thereof as seen from the outside of the left door of an automobile, and showing the parts in unlatched position in dot and dash lines;

Fig. 2 is a top plan view of the lock mechanism illustrated in Fig. 1;

30. Fig. 3 is a broken side elevational view of the inner handle and associated mechanism as observed from the rear of Fig. 1;

Fig. 4 is an enlarged sectional view substantially in the plane of line 4—4 of Fig. 1;

40. Fig. 5 is a bottom plan view of the structure illustrated in Fig. 3;

Fig. 6 is a plan view of an improved keeper mechanism forming a part of the present invention;

45. Fig. 7 is an elevational view of the keeper mechanism as observed from the right of Fig. 6;

Fig. 8 is a fragmentary elevational view of an automobile door showing the locking mechanism from the inner side of the door with panel portions broken away for greater clarity of illustration.

50. Fig. 9 is a view corresponding to Fig. 1 depicting a modification of the invention and showing the locking elements in normal position;

Fig. 10 is a view of the reverse side of the mechanism shown in Fig. 9;

Fig. 11 is a bottom plan view as observed in the direction of the arrow 11 in Fig. 9;

Fig. 12 is a top plan view of means for yieldably maintaining the key operated spindle in neutral or normal position;

Fig. 13 is an end view of the swinging bolt constructed in accordance with the modified embodiment of the invention;

Fig. 14 is a bottom plan view of the swinging bolt;

Fig. 15 is a view corresponding to Fig. 9 showing the dogging plate in locking position in full lines and in unlocking position in broken lines;

Fig. 16 is an opposite side view of the left portion of Fig. 15;

Fig. 17 is a fragmental side elevational view showing a modified form of window-locking mechanism with the associated signal device; and

Fig. 18 is a horizontal sectional view as observed in the plane of line 18-18 in Fig. 17.

Referring now in detail to the drawings by the use of reference characters, D designates an automobile door, a panel of which is suitably recessed to accommodate the lock mechanism about to be described. A housing base plate 10 is secured to the inside of the door over the recess therein and includes a right angular flange 11, the flange 11 being secured in a recess in the free edge of the door and the plate 10 being secured to the door as at 12, and the flange 11 is apertured for reception of a latching bolt 13.

The bolt 13 is movably disposed within a recess 14 in a locking or dogging plate 15 which plate is slidably retained on the housing plate 10 by means of a guide lug 16 and an angularly bent edge portion of the housing cover plate 17. The locking bolt 13 is rigidly carried by a bolt plate 18 having shoulders 19 at its rear edge which are normally yieldably maintained against stop lugs 20 on the housing base plate 10 by means of a spring 21 engaging the locking bolt 13.

A stud 22 is carried by the bolt plate 18 and projects through an elongated slot 23 in a link 24, one end of which is connected to the locking plate 15 as at 25. A lost motion connection is thus provided between the bolt 13 and the operating link 24 for reasons later to appear. The locking plate 15 is movable by the inner handle with the link 24 to outside handle dogging position, as shown in full lines in Fig. 1 and to undogged position by the key, as indicated in dot-and-dash lines in the same figure.

This dogging and undogging arrangement is similar to that of my patented structure referred to, but as distinguished therefrom the locking plate is movable a relatively short distance with a corresponding slight movement of the connected parts so that substantially less frictional drag on the key results. The major operations of the locking and unlocking movements are thus transferred to the handles.

The outside door handle 26 supports on the squared shaft 27 thereof a roll-back 28 having a projection 29 and a relatively narrow shoulder 30, which are substantially at right angles to each other. The projection 29 is engageable with the bolt plate 18 for retracting the bolt 13 upon downward movement of the outside handle 26, and the shoulder 30 is engageable with a shoulder 31 on the locking plate 15 when the plate is in its forwardly moved position as illustrated in full lines in Fig. 1 occasioned by upward lifted move-

ment of the inside handle 32 which positively shifts the link 24 for dead-locking the roll-back against movement and thereby locking the handle 26. When the plate 15 is shifted to the position indicated by dot-and-dash lines in Fig. 1 however by movement of the key in one direction, the normal bolt retracting movement of the roll-back 28 is permitted. The plate 15 is preferably provided with spaced notches 15^a for selective reception of a detent spring 15^b for yieldably retaining the plate in locked or normal position.

The locking plate 15 is moved to either the roll-back dogging or undogging positions by manual up and down movements of the inner handle 32, and is movable to undogging and dogging positions by means of an outside operated key mechanism in accordance with one embodiment of the invention.

For moving the plate 15 of Fig. 1 by the key mechanism an obliquely positioned lug 33 is disposed on the plate 15 and is engageable by a finger 34 carried by the key operated lock spindle part 35 having a squared operating shaft aperture 36.

To the inside of the door D and laterally of plate 10 is secured, as at 37, a mounting plate 38 in which plate and bracket 38^a is journaled the inside handle actuated shaft 39 which carries a lever 40 to the free end of which is pivotally connected, as at 41, one end of an operating link 42. The opposite end of the link 42 is pivotally connected at 43 to the link 24, whereby the locking plate 15 is selectively movable to roll-back dogging and undogging positions.

Rigid with the shaft 39 is a block 44 having an extension 45 on which is secured the hub 46 of the inner handle 32 which upon movement in an upward direction moves the plate 15 to a forward roll-back locking position through shaft 39, lever 40 and links 42 and 24, and which upon downward movement shifts the plate 15 to the rear or roll-back unlocking position. The handle upon further downward movement moves link 24 rearwardly until the stud 22 engages the forward end of slot 23, whereupon the bolt plate 18 and its latching bolt 13 are retracted.

The lock according to the present invention includes means for latching the inside handle 32 in deadlocking position and while being generally similar to that disclosed in my patent, differs therefrom as will appear in the description following. The block 44 is provided with an aperture 47 extending transversely to the shaft 39 and through which aperture extends a swinging bolt 48. The bolt 48 is pivotally mounted intermediate its ends, as at 49, within the aperture 47 and with its opposite ends projecting beyond the block as clearly indicated in Fig. 4. One end of the swinging bolt 48 is yieldably maintained against the keeper flange 50 on an angle plate 51 secured to the plate 38, as at 52, by means of a plunger 53 extending through an arcuate slot 53' in plate 38, which is urged against the other end of the swinging bolt by means of a coiled spring 54 disposed within a housing 55 secured as by a clip 56 to one end of the shaft 39, as shown in Fig. 1 and directly against the plate 38 as will be later described in connection with Fig. 9. The yielding plunger 53 is provided with an annular flange 57 against which one end of the coiled spring 54 bears and which flange serves to retain the plunger in position against one end of the swinging bolt 48.

At this point, it is to be particularly noted that the block 44 and housing 55 are disposed at op-

posite sides of plate 38 which provides a more balanced arrangement than in the patented structure, wherein the block and housing are disposed at the same side of the plate. The keeper flange 50 terminates in a shoulder 58 against which the swinging bolt 48 bears under action of spring 54 when the handle 32 is moved to upper position with the plate 15 in dogging position, and which position of the plate restricts any further upward movement of the handle. By reference to Fig. 10 it will be noted that this operation is accomplished by the cooperation of a lug on the swinging bolt 48 with a notch in the plate 38.

In order to retract the swinging bolt 48 from latched engagement with the shoulder 58 to permit downward movement of the inner handle 32, means is provided in the form of a plunger 59 extending through a bore 60 in the block extension and having an annular shoulder 61 surmounting a tubular upper end member 62 having threaded bore engagement with the push button 63.

The plunger 59 thus provided with the push button 63 is adapted for thumb contact therewith to force the plunger inwardly to retract the swinging bolt 48 from engagement with the shoulder 58 when the handle 32 is grasped to swing same downwardly. Thus, as in my patented structure, two movements of the parts just described at right angles to each other, are necessary in order to move the inner handle 32 from latched position.

An essential part of the present invention in combination with the locking plate releasing means includes an operative connection with the key operated tumbler lock indicated at 35 for releasing the bolt 48 from latched engagement with the shoulder 58. Such means comprises a cam bar 64 guidably and slidably positioned on the base plate 65 of the angle plate 51. The cam bar carries headed studs 67 extending through elongated guide slots 68 in the plate 65, Fig. 5. The cam bar 64 is provided with a wedge or cam-shaped nose 69 operative to move under the adjacent curved end of the bolt 48 to raise the same out of engagement with shoulder 58 upon movement of the cam bar toward the shoulder.

The cam bar 64 at its end opposite the cam nose 69 is pivotally connected as at 70 to one end of a link 71 whose opposite end is pivotally connected at 72 to the free end of an elongated arm 73 rigid with the key operated lock spindle 35. The lock spindle 35 is provided with a finger 74 engaged by the free end of a curved leaf spring 75 having its opposite end secured, as at 76, to the plate flange 11. A stop lug 77 is formed on plate 10 and is engageable by the base of arm 73 through the action of the spring 75 which returns the lock spindle to normal position and with the arm 73 in engagement with the lug 77, the finger 34 at this position being spaced from the locking plate retracting lug 33.

The arrangement of cooperating parts just described is such that the swinging bolt 48 is disengaged from the shoulder 58 by the action of the cam bar nose 69 in opposition to the action of the spring 54 against the opposite end of the bolt at the time the finger 34 has moved to a position to engage the lug 33, whereupon further rotation of the lock spindle 35 will cause finger 34 to move the lug 33 and locking plate 15 a distance only substantially equal to the width of the shoulder 30, as indicated by dot-and-dash lines in Fig. 1, to permit movement of the roll-back. During such movement of the locking plate the link 73

will move laterally to engage a stop 79 on the plate 10 which limits the movement of the key as well as that of the locking plate to a distance rearwardly just sufficient to permit movement of the roll-back by withdrawal of the locking plate from beneath shoulder 30. Thereafter the spring 75 will automatically return arm 73 to normal position in engagement with stop lug 77, as well as retracting the cam bar 64; then the key may be removed.

With the plate 15 in roll-back undogged position the bolt plate 18 together with the bolt 13 may be retracted by either the outer handle 26 or the inner handle 32. In this arrangement the locking plate is moved to roll-back dogging position by means of manual upward movement of the inner handle 32.

In the structure of my patent referred to, the locking plate is provided with a recess to permit retraction of the latching bolt 13 when the locking plate is in dogging position. In the present construction, such recess is not provided and the latching bolt 13 is locked against retraction when the locking plate is in dogging position, and in order to provide for closing of the door upon dogging the roll-back from the inner handle, the present locking mechanism includes a novel keeper structure illustrated in detail in Figs. 6 and 7 and which includes a rectangular plate 80 to which is suitably secured the foot portions of an angular housing plate member 81, the ends of plate 80 and feet of plate member 81 being apertured as at 82 for receiving securing means for mounting the keeper within a suitable recess in a door jamb.

A plate 83 may be secured to the inner face of plate 80 and plates 80 and 83 are provided with aligned rectangular apertures for projection therethrough of bolt members 84 and 85 which are respectively provided with shanks 86 and 87 which in turn are respectively surrounded by springs 88 and 89 having their opposite ends bearing against the bolt members and the portion of plate member 81 which is spaced from and parallel with plates 80 and 83. The shanks 86 and 87 extend through openings in the portion of the plate member 81 referred to as well as through aligned openings in a cushion pad 90 against which rest cotter pins 91 extending through openings in the shanks adjacent their ends. The cushion pad functions to cushion and quiet the impact of the bolt members upon outward movement of the bolt members under action of the springs after having been depressed by action of the latching bolt 13.

The keeper is attached as in Fig. 8 and the bolt member 84 which is smaller and backed by a weaker spring than bolt member 85 is first depressed and passed by the locked latching bolt 13; after which bolt member 85 is depressed and passed by the latching bolt in the full closed position of the door.

While the construction herein disclosed is like that of my patent referred to, to the extent only that the door can be closed when the roll-back is dogged, it is to be observed that the present structure renders it substantially more difficult to open the door through manipulation of the latching bolt members. As in the patent referred to, means are provided for locking a window W pivotally mounted in the door in the usual and well known manner. Such locking means comprises an arm 92 secured as at 93 to a block 94 secured to the outer face of the link 42. A link 95 has one end pivotally connected at 96 to the

upper end of arm 92 and its opposite end pivotally connected at 97 to the shorter end of a lever 98 pivoted to the door at 99, and the free end portion of the longer end of the lever being receivable in a keeper 100 secured to the window, the lever being swung on its pivot 99 to lock and unlock the window upon dogging and undogging of the locking plate 15.

The lever 98 at its upper free end is provided with a signal 101 which may comprise a disc-like casing 102 having a central eye-attracting member 103, such as the common reflecting button members carried on rear auto tags and the like, or the button, preferably made of glass or the like, may contain radio-active material so as to be visible in the dark. The lever 98 is preferably so pivoted and connected with the link mechanism that the member 102 is normally concealed as indicated in dot-and-dash lines at 101^r in Fig. 8 when link 42 has moved to such extent as to undog the roll-back 28 whereby is provided a convenient and dependable visible indicator as to whether the roll-back is dogged or undogged. However, when the locking plate 15 is in normal operating position, as in Fig. 9, the signal will be at the position 101^r, and of course the signal will drop still further upon retracting the bolt 13 by the inner handle.

In accordance with the embodiment of the invention disclosed in Figs. 9 to 16 inclusive, the previously described structure is substantially simplified while at the same time rendered more efficient particularly from the standpoint of latching and unlatching the inner handle and the connecting means with the locking plate for the outer handle. In these figures all of the parts corresponding to those above referred to in connection with Figs. 1 to 5 are designated by like reference numerals, and only those parts differing from the first embodiment will be particularly described.

In accordance with this preferred embodiment of the invention, the plate 15 is provided with a lug which is generally L-shaped and embodies a finger engaging portion 105 and an opposing finger engaging portion 106. The lock spindle 35 is yieldingly retained in normal key receiving position, as shown in Fig. 9, by means of an elongated leaf spring member 107 having one end thereof engaged with the spindle, as at 108, and the other end thereof movably received in a slot 109 in the head of the stud 110, rotatably supported in plate 10, as by a reduced portion 111. The slot 109 has opposed convex walls for engagement by the opposed faces of the spring upon rotation of the spindle 35 to which the spring is attached. By this means the spindle is normally maintained in the position of Fig. 9.

The spindle is further provided with a finger 34' which corresponds with the finger 34 of the first embodiment and which may be integral with the arm 73, as shown. This finger is curved rearwardly so that its end portion will engage the lug portion 105 upon rotation of lock spindle 35 by the usual key, not shown, for slidably moving the plate 15 to undog the bolt 13, as is shown in broken lines in Fig. 15. The lock spindle 35 is provided with a second finger 112 which is engageable with the lug portion 106 upon movement of the spindle in an opposite direction for moving the locking plate to dogging position.

The arm 73 and link 71' function as in the first embodiment with arm 73 engaging a stop 79' upon retraction of the locking plate to the position shown in broken lines in Fig. 15. The

link 42' is, however, substantially different in construction as well as function from the corresponding link 42 in the first embodiment. This link, which in common with link 42, interconnects the locking plate 15 and the inside handle now further functions to support and guide the cam bar 64', which in the first form, is supported by an angle plate 51 secured to the fixed plate 38. Accordingly, the movable link 42' is formed with a bottom cam bar supporting flange 113, Fig. 11, which is provided with an elongated slot 114 for slidably receiving a lug or screw member 115 secured to the under side of the cam bar.

15 The cam bar 64' is also provided at one side with a second screw member 116 which is slidable in an elongated slot 117 in the link 42'. A spacer sleeve 118, through which the screw 116 extends may be provided between the link 42' and the link 71' to maintain parallel relation therebetween, as shown in Fig. 11.

16 In accordance with this latter embodiment of the invention, shown in Figs. 10, 13 and 16, the swinging latch bolt of the inner handle 32 is modified in the provision of a laterally extending foot portion 119, from the lower face of which projects a rounded holding or dogging lug 120. This lug 120 is automatically engageable in a notch 121 in the forward edge of fixed plate 38. When the bolt 48 is swung to one limit of its movement the plate 38 preferably will be further cut out as at 122 to provide for better action of the cam bar 64'.

35 The simplicity of this embodiment, as compared with the first described embodiment, will be appreciated upon comparison of Figs. 2 and 11. In Fig. 2 the link 71, which actuates the cam bar, crosses over the link 42 whereas in the present embodiment links 42' and 71' are parallel and the cam bar is supported for reciprocation directly on the link 42', thereby omitting the fixed angle plate 51 of the first embodiment, etc.

36 Furthermore the arrangement just described provides a better balanced construction, and by 45 providing the straight line 71' and movable bolt mounting, less resistance is offered to the turning of spindle 35 by the key.

46 The mechanism is shown in normal position in Fig. 9 with locking plate 15 retracted a distance equal to the length of the projecting bolt 13 and in which position the stud 22 is at the right hand end of slot 23, whereby the bolt 13 may be directly retracted upon downward movement of the inner handle 32.

55 In Figs. 15 and 16 the locking plate 15 is shown in solid lines in roll-back dogging position and the lug 120, of swinging bolt 48 engaged within the notch 121 of fixed plate 38. The inner handle is thus shown latched or dogged against movement until the lug 120 is again retracted, either by the key or the button 63, and thus moved to the undogged position on the face of the plate 38, shown in dotted lines in Fig. 16.

56 The foot 119 on the swinging bolt 48 serves to 65 limit the depression or movement of the lug 120 through the notch 121 so that the lower surface of the lug is supported or engaged by the bevelled end surface 64'' of the cam bar 64' for easy lifting of lug and bolt 48 from the notch 121 upon 70 slight movement of the cam bar thereunder, by the link 71' and arm 73; all as indicated in broken lines in Figs. 15 and 16. The swinging bolt 48 is slightly rotated from its latching alignment with the notch 121 during the movement of the locking plate 15 away from shoulder 30 by the

angular engagement of the forward lifting cam face 64" against the rounded underside of the latching lug 120, as in the first embodiment.

By the provision of the slots 114 and 117 in the movable link 42, together with screws 115 and 116, the link 42' is freely movable by the inner handle 32 without effecting longitudinal movement of the cam bar 64" which is retained in position relative to plate 38 by link 71", connected with the normally stationary lock spindle 35.

With the locking plate 15 in normal position, as shown in Fig. 9, the same may be readily moved to the roll-back dogging position of Fig. 15 by key rotation of the spindle 35 in an opposite direction, whereby the finger 112 will be caused to engage with the lug portion 106 and move the locking plate from the position of Fig. 9, to that of Fig. 15.

A modified arrangement of locking means for the window W is illustrated in Figs. 17 and 18, wherein the keeper 100' is provided with an inwardly curving projecting end 125, thereby providing a camming surface 126 for the swinging keeper portion 127 of the signal supporting lever 98. The keeper 100' is shown provided with an operating ring-retaining portion 128 within which is received a hand-engageable ring 129 for drawing the window to a closed position. By the provision of the camming surface 126 the window may be forced to a tightly closed position by the normal movement of the swinging bolt 127 to secure the sash even though it may not be all the way closed by the ring 129 or other operator. The lever 98, carrying the signal 103 and window securing bolt 127 may be connected for operation by the handle and key operated parts, in association therewith, whereby the condition of these normally concealed operating parts within the automobile door may be known at a glance from the inside or outside of the car.

From the foregoing detailed description of the improved latching mechanism, it will be appreciated that the same is generally similar both in construction and in operation to that of the patent referred to. The present structure, however, provides for movement of the locking plate to undog the roll-back by means of improved key actuated mechanism whereby little effort is required in turning the key and with consequent little strain on the key, the strain being taken up by the outer handle.

The present construction also provides for readily ascertaining whether or not the roll-back has been dogged by means of the visual signal or indicator and the construction also includes other improved features which render the latching mechanism dependable and easy of operation.

Changes may be made in details of construction without departing from the scope of the invention as defined in the subjoined claims.

I claim:

1. In an automobile door lock comprising a spring-pressed latch bolt, an outside handle operated roll-back operative to retract the latch bolt, a slideable locking plate operative to latch the roll-back against movement and unlatch same for movement; an inside door handle having an operative connection with the locking plate, latch means associated with the inside handle automatically operative to latch the handle against movement when the locking plate is moved to roll-back latching position, and key operable means for moving the locking plate to roll-back unlatching position and unlocking the inside handle; the improvement which comprises a rela-

tively narrow shoulder on the roll-back beneath which the locking plate rests when in latching position, and means included in the key operable means for limiting retraction of the locking plate to a distance substantially equal to the width of said shoulder whereby to provide easy manipulation of the key operable means.

2. The structure of claim 1, wherein the key operable means is yieldably urged to normal key inserting and retracting position.

3. The structure of claim 1, wherein the key operable means comprises an elongated arm, a finger on the arm engageable with a lug on the locking plate for moving the same to roll-back unlatching position, a link connection between the arm and the inside handle latch means, and a stop engageable by the arm to limit movement thereof.

4. In a lock for an automobile door having a movable sash, an outside latch bolt operating handle, an inside handle means operatively connected with the inside handle for latching the outside handle against latch bolt retracting movement means associated with the inside handle automatically operative to latch the same upon movement thereof to outside handle latching position, and means operatively connected with said first means operative to latch the sash against movement when the inside and outside handles are in latched position, the improvement which comprises a visible indicator supported by said last means and movable thereby to a position visible through the sash when said handles are in latched position.

5. A latch mechanism for an inside automobile door handle comprising a base plate having an arcuate slot therein, a bracket supported by the base plate and having a portion in spaced relation thereto, a handle operated shaft journaled in the plate and said portion of the bracket, a block unitary with the shaft and disposed at one side of the plate, a housing supported by the shaft and disposed at the opposite side of the plate, a rocking bar pivotally supported within an aperture in the block, a shoulder engageable by one end of the bar, a spring urged plunger supported by the housing and extending through said slot in bearing engagement with the other end of the bar, and a plunger manually movable through the block and engageable with the bar intermediate its pivot and said first plunger for moving the bar from engagement with the shoulder.

6. An automobile door lock comprising a pair of spaced mounting plates, a latch bolt slidably supported on one of the plates, an outside handle rotatably supported in said last plate and operative upon movement thereof in one direction to retract the latch bolt, an inside handle rotatably supported by the other plate, a locking plate slidably mounted on the first named plate for opposed movements to dog and undog the outside handle against rotation, a linkage connection between the locking plate and inside handle having a lost motion connection with the latch bolt, means supported by the second named mounting plate operative upon movement of the inside handle to a position in which the locking plate is moved to outside handle dogging position to lock the inside handle against rotation, and key operated means slidably supported on the linkage connection for disengaging said locking means.

7. An automobile door lock according to claim 6, wherein said inside handle locking means comprises a pivotally mounted spring-pressed swing bolt bodily movable with the inside handle

11

and having a lug adjacent one end thereof, and a notch in an edge of the second named mounting plate receiving said lug upon movement of the inside handle to said outside handle dogging position.

8. An automobile door lock according to claim 6, wherein said key operable means comprises a cam bar slidably supported on the linkage connection providing for independent movement of the linkage connection and cam bar by the inner handle and key respectively.

9. An automobile door lock comprising a pair of spaced fixed mounting plates, an outside handle rotatably supported in one of the plates, an inside handle rotatably supported in the other plate, a latch bolt slidably supported by the first plate yieldably retained in extended position, a roll back movable by the outside handle and engageable with the latch bolt for retracting same, a shoulder on the roll back engageable with a locking plate slidably supported on the first named mounting plate for dogging the roll back against latch bolt retracting movement, a link interconnecting the locking plate with the inside handle for movement of the locking plate to roll-back dogging and undogging position, a lost motion connection between the latch bolt and link providing for retraction of the bolt by the outside handle without effecting movement of the inside handle, a lug connected with the inside handle for movement therewith and spring pressed against a face of the second mounting plate, a notch in an edge of the last named plate engageable by the lug for locking the inside handle against rotation upon movement thereof to a position in which the locking plate is moved to roll-back dogging position, and key operable means for retracting the lug from the notch and moving it onto the face of the plate for unlocking the inside handle.

10. The structure according to claim 9, wherein said key operable means comprises a cam bar slidably supported on said link, a second link disposed laterally of the first link and parallel therewith, a pivotal connection between the cam bar and one end of said second link, and an arm supported for rotation by a key and having pivotal connection with the other end of the second link.

11. The structure according to claim 9, wherein said key operable means comprises a cam bar slidably supported on said link, a key operable spindle rotatably supported in the first mounting plate, an arm rigid with the spindle and movable therewith, a second link interconnecting the cam bar and arm, a lug supported by the locking plate, a finger rigid with the spindle on each side of the lug for movement of the locking plate to dogging or undogging positions upon engagement of one or the other of the fingers with the lug, and yieldable means for retaining the spindle in normal position.

12. In a locking mechanism for automobile doors, a roll-back operated latch bolt, a slidably supported locking plate movable to and from position wherein the latch bolt is dogged against movement and undogged for movement, a lug on the locking plate, a key operable rotatable spindle, fingers carried by the spindle for engagement with opposite sides of the lug for moving the locking plate to and from dogging position, a rotatably supported stud having a slot in the free end thereof, and a leaf spring having one end thereof secured to the spindle and the other end thereof loosely engaged in the slot for yieldably

12

retaining the spindle in normal key receiving and removing position.

13. The structure according to claim 12, wherein in opposed walls of the slot are convex for rolling engagement of the leaf spring therewith.

14. An automobile door lock comprising a bolt slidably mounted in an edge of the door, an outside handle and an inside handle mounted on the door for independent operation, lost motion operating means connecting the bolt with said handles, dogging and undogging means for each handle connected to the inner handle for operation thereby, and key operated means mounted in the door adjacent the outer handle and carried in part by said lost motion means, said last mentioned means being associated with each handle to also move the dogging and undogging means to secure or free both handles by the key operated means.

15. An inside latching bolt operating handle mechanism for automobile doors comprising a mounting plate having a recess therein, an inside handle secured to a shaft rotatably journaled in the mounting plate, an elongated bolt pivotally supported by the shaft for swinging movement relative to the plate and confined by the shaft for rotative movement therewith, yieldable means bearing against one end of the bolt for urging the other end thereof against the mounting plate, a lug carried by said other end of the bolt engageable in said recess upon movement of the handle in one direction to a pre-determined position for holding the handle against movement in a reverse direction, and movably operable means supported by the handle and shaft for releasing the lug from the recess against the action of said yieldable means.

16. The structure according to claim 15 wherein said bolt is pivotally supported in an aperture in a block rigid with the shaft and disposed at one side of the mounting plate, and wherein said yieldable means is supported by the shaft at the opposite side of the mounting plate.

17. An inside latching bolt operating handle mechanism for automobile doors comprising a rectangular mounting plate having an arcuate slot therein, a bracket secured to one face thereof, a handle rigidly supported by a shaft rotatably journaled in the plate and bracket, a block rigid with the shaft and engaging the face of the plate opposed to the bracket, an aperture in the block, a bolt disposed within the aperture and confined by opposed walls thereof for rotative movement with the handle, said bolt having the opposite ends thereof projecting beyond corresponding ends of the block and being pivotally supported thereby for swinging movement in a plane normal to the plate, yieldable means supported by the shaft outwardly of the bracket and including a plunger extending through the arcuate slot in the plate and engaging one end of the bolt for urging the other end thereof toward the plate, an abutment supported by the plate engageable by said other end of the bolt upon movement of the handle to a pre-determined position in one direction, and manually operable means supported by the handle and shaft for releasing said bolt from the abutment for movement of the handle in a reverse direction.

18. The structure according to claim 17 wherein said abutment is provided by a notch in one edge of the plate, and wherein said bolt is provided with a lug engageable in the notch upon movement of the handle to said predetermined position.

19. The structure according to claim 17 wherein said shaft rigidly supports a lever disposed between the plate and bracket for pivotal connection with a latching bolt operating link.

20. Inside handle latching bolt operating mechanism for automobile doors comprising a mounting plate, a shaft rotatably supported in the mounting plate and having an inside handle secured thereto, a bolt pivotally supported by the shaft and rotatable therewith, yieldable means rotatable with the shaft operative to urge one end of the bolt toward the mounting plate, cooperative engaging means carried by the plate and bolt operative under the action of said yieldable means to lock the handle against movement when rotated to a predetermined position, a latching bolt operating link connected with said shaft, and key operable means slidably supported by said link for releasing said cooperative engaging means.

21. Combined latching and signaling means for the horizontally swingable sash of an automobile door having an adjacent sash, comprising a keeper secured to the swingable sash and having a free end spaced from the swingable sash and providing a camming surface, a latch pivotally mounted on the door for swinging movement in an arc adjacent the lower edges of both sashes toward and from the keeper and operative to force the swingable sash closed upon engagement with said camming surface, and an indicator movably carried by the door and operable with the latch on engagement with the keeper to move the indicator into a position within the margin of one of the sashes so as to be visible from either side thereof and to be retracted from said position so as to be concealed upon movement of the latch out of engagement with the keeper.

22. Combined locking and signaling means for an automobile door having a window, comprising a bolt mounted in an edge of the door, an outside handle and an inside handle mounted on the door for independent operation, lost motion means connecting the bolt with said handles, dogging and undogging means for each handle connected to the inner handle for operation thereby, key operated means mounted in the door adjacent the outer handle and carried in part by said lost motion means, said last mentioned means being associated with each handle to also move the dogging and undogging means to secure or free both handles by the key operated means, and an indicator connected to the lost motion means for operation by said dogging and undogging means to move the indicator to positions within and without the sight range of the window for indicating from both sides of the door the condition of the bolt operating parts for operation of the handles.

23. An automobile door lock comprising a spring latching bolt, an outer handle connected with a roll-back operative to release the bolt, a slidably mounted roll-back locking plate, a relatively narrow shoulder on the roll-back with which the locking plate coacts when in roll-back locking position to lock said roll-back and outer handle against movement, an inner handle, a link connection between said inner handle and said locking plate for moving same to and from said roll-back locking position upon predetermined movement of the inner handle, a lost motion con-

nection between said link connection and said bolt for retracting the bolt upon further movement of said inner handle after moving said locking plate from roll-back locking position, and rotatable key operable means for moving the locking plate from roll-back locking position, and means limiting the movement of the locking plate by the key operable means from said roll-back locking position to a distance substantially equal to the width of said shoulder.

24. An automobile door lock comprising a spring latching bolt, an outer handle connected with a roll-back operatively engageable with the bolt for releasing same, a slidably mounted roll-back locking plate, a relatively narrow shoulder on the roll-back with which the locking plate coacts when in roll-back locking position, a key operated rotatable spindle, cooperating means carried by the locking plate and spindle operative to release the plate from engagement with the shoulder upon rotation of the spindle in one direction, stop means operative upon rotation of the spindle in said one direction to arrest its movement when rotated through an angle of less than 90° and with corresponding movement of the locking plate a distance substantially equal to the width of said shoulder, and means for automatically returning the spindle to normal position for removal of the key.

25. An automobile door lock comprising a bolt mounted in one edge of the door, an associated slidably mounted plate movable relative to the bolt for unlocking the bolt in one position of the plate, an outer handle operated roll-back engageable with the slideable plate for moving it to said bolt unlocking position, a second plate having a lost motion connection with the first plate and movable relative thereto for dogging the roll-back, an inner handle having a normal inoperative position, a link connection between said inner handle and said second plate for moving same to roll-back locking position upon predetermined movement of the inner handle in one direction from said normal position and for undogging the roll-back and unlocking the bolt upon movement in another direction from said normal position, and key operable means operative from the outside of the door and having lost motion connection with the second plate for moving said plate to roll-back undogging position, and said second plate being thereafter movable by the roll-back to restore the inside handle to its normal position when the first plate is being moved to bolt unlocking position by the outside handle.
